MEANS FOR PACKING TIN AND LIKE PLATES AND INNER CONTAINER THEREFOR

Norman Bishop and Ernest R. Garrod, London, England, assignors to Shell Development Company, San Francisco, Calif.

Application October 22, 1932, Serial No. 639,088
In Great Britain October 30, 1931

13 Claims. (Cl. 226—2)

This invention relates to means for packing tin and like plates and inner containers therefor.

It is known to those skilled in the art that the strength of a package containing tin plates and the like is dependent upon how tightly the tin plates, when lying flat, have a slight set or buckle amounting in some cases in a box of 124 tin plates to as much as $\frac{3}{8}$ ". Metal cases hitherto used for the packing of tin plates, have usually been made with a sufficient depth to accommodate the plates in their set or buckled condition.

According to the present invention the plates are flattened under pressure to remove the set or buckle. In one way of carrying out the invention the tin plates are arranged or stacked in shallow box-like inner containers preferably having stiff sides, the depth of each container being preferably the same as the thickness of a stack when flattened. The lid of the container is then partially closed (complete closing being prevented by the buckle of the plates). The inner container is now passed through a press which flattens the stack and closes the lid and is then inserted into an outer casing which is located close to the press, the said inner container forming a protective lining between tin plates and the outer casing.

The outer case may be and preferably is of the kind described in United States Patent No. 1,730,070 of 1st October, 1929.

Among the advantages to be gained by compressing the tin plates whilst in the papier mâché container and automatically inserting the plates, together with the papier mâché container, into the metal box, are the following:

Any partial collapsing of the filled case due to compression is eliminated, since the metal case is made smaller to accommodate the compressed plates and form a tight and compact package.

The speed of packing is greatly increased with less labour (estimated speed of packing is one complete box every 12 seconds).

The number of times the tin plates are handled is cut down, the plates being handled only once, that is, from inspection bench straight into the papier mâché container.

The insertion of tin plates and papier mâché lining en bloc into the metal case entirely overcomes any chafing of the papier mâché which would occur in the case where the plates are inserted into a papier mâché lined metal case. This chafing raises fluff which is deposited on the tin plates and is detrimental to the working of the latter.

An inner container suitable for use in carrying out the present invention and adapted to conform to the dimensions of the flattened plates without substantially increasing the overall size of the package and which shall at the same time be collapsible for storage and transport purposes when empty, is illustrated in Figures 1 to 3 of the accompanying drawings, Figure 1 being a plan view of the container in the collapsed or unfolded form, Figure 2 being an isometric view of the folded container and Figure 3 a section. Figure 4 is a side elevation of machine suitable for packing the tin plates, Figure 5 is a plan view thereof and Figure 6 is an end elevation. Figure 7 is a sectional view of an alternate container for tin plates. Figure 8 is an elevation of clamping levers 36 of the machine at rest. Figure 9 is an elevation of clamping levers 36 of the machine in operating position. Figure 10 is a plan view showing detail of ram 5 of the machine. Figure 11 is an elevation of cams 13 and 30 showing clutch arrangement. Referring to Figure 2 the container comprises relatively thick ends *a* and *a*₁ and sides *b* and *b*₁, which may consist for example of plywood, wood or wood pulp, preferably about $\frac{1}{4}$ " thick said ends and sides being attached (e. g. stitched or glued) to a bottom portion *C* of papier mâché or the like having the relative positions shown in Figure 1. The inner container is folded along the dotted lines in Figure 1 to form a tray-like structure having side flaps *d* and *d*₁ end flap *e* and top cover *f*, adapted when folded entirely to cover the tin plates. It will be seen that the thick sides and ends are attached to the papier mâché in such a way that when the container is folded the papier mâché forms a complete covering for the tin plates, and the thick plywood ends and sides which are on the outside of the container do not come into contact with the tin plates, thereby preventing the setting up of rust, should the wood be at all damp. Another advantage of assembling the wood strips on the outside of the container, and allowing the papier mâché to form a complete covering, is to prevent the tin plates, when packed loosely into the container without having been compressed, from resting on the thick sides and edges, thereby causing bending of the plates on compression. This feature is clearly shown in the sectional view in Figure 3.

The ends *a* and *a*₁ are made equal in length to the overall width of the container and sides *b* and *b*₁ are made to butt against the inside of ends *a* and *a*₁ in order that sides *b* and *b*₁ may take the thrust when the inner container and tin plates are forced into the outer case in a manner to be

described later. The end flap *e* is provided for other reasons, which will be described in the operation of the packing machine.

The tin plates together with the inner container above described can be readily packed into an outer metal case of the type described in United States Patent 1,730,070, by means of the machine diagrammatically illustrated in Figures 4, 5 and 6 of the accompanying drawings. Referring to 10 these figures:

The machine is provided with a plurality of parallel rollers 1, rotatably mounted between outside frame members 2 and inside members 3, so as to form a bed on which rests the bottom of the 15 inner container. The outside members 2 are extended upwardly to form the supporting sides for the inner container. A movable abutment or back stop 4 and a ram 5 are provided to form respectively the back and front supports for the 20 ends of the inner container. It will be seen therefore that when the machine is in its normal position (i. e. the position shown in the drawings) a tray-like formation is provided for the folded papier mâché container which is placed in position 25 therein. The outer tubular container is held in position to receive a fully loaded compressed inner container (which is discharged through rollers 6 and 7) by means of a tiltable table 8, pivoted about a horizontal axis at 9, said table being tilted by a link 10 attached to a lever 11 pivoted at 30 12 and a cam 13.

Upstanding supporting members 14 and 15 are provided in which is mounted horizontally and rotatably a roller 6, the distance between the peripheries of rollers 6 and 7 being equal to the 35 depth of the inner container. The roller 6, however, may be provided with eccentric bearing bushes housed in the members 14 and 15, to allow of adjustment of the distance between the rollers 40 6 and 7 for varying depths of containers. Co-axially mounted and free to swing on the spindle 16 of roller 6 are arms 17 adapted to carry horizontally mounted and free to rotate there-between a large and weighted roller 19. Co-axially 45 mounted and free to swing about spindles 16 and 22 are locating or guiding members 20 and 21, so arranged that they may move substantially tangentially to the peripheries of rollers 6 and 7 respectively. This freedom of movement is provided in order to enable the loaded outer tubular 50 container, the mouth of which is located over the parts 20 and 21 when the inner container is being forced therein to swing clear, when the tilting table 8 operates.

Movable guides 23 are provided to facilitate the 55 loading of the tin plates into the papier mâché container. These guides are linked together by means of link 24 and are rotatably mounted on a spindle 25, and are rotated free of the papier 60 mâché container when the machine is ready for operation. The remaining parts of the machine will now be described in terms of the operation of the machine as a whole.

When the tin plates have been loaded into the 65 papier mâché container a lever 26 is pulled, allowing the engagement of a suitable clutch 44 which is mounted on shaft 27 as shown in Figure 11. The engagement of this clutch causes two cams 30 and 13 to rotate together with the shaft 70 27. A lever 28 pivoted at 29, having a roller 29' adapted to engage the cam 30 is moved thereby, thus lowering the back stop 4, below the level of the machine bed. This action takes place before the ram 5 commences to move forward under 75 the action of an adjustable link 31, which is piv-

oted to the ram 5 at 32, and to a rocking lever 33 at 42, the rocking lever 33 being pivoted at the base of the machine at 12. A roller 34 housed in the rocking lever 33 is attached to a connecting link 35, which in turn is attached to a stud 43, which forms a crank pin on the cam 13, thus allowing the ram to move forward in a horizontal plane forcing the papier mâché container with its full complement of tin plates, into a metal tubular container which is placed on the tilting table 8, with its open end located over members 20 and 21. On the first movement of the ram two back clamping levers 36 and 37 (Figure 5) close down on the back end of the papier mâché container compressing the tin plates down within the container, at the same time folding the flap *e* into the container, thus preventing any movement of the tin plates backward, whilst being forced under the weighted roller 19 and through the set gap between the rollers 6 and 7. Referring to Figures 8, 9 and 10, the clamping effect of the back clamping levers is brought about as follows. Levers 36 and 37 are pivoted intermediate the ends thereof to the ram 5 as indicated at 38, the extended rear portions of levers 36 and 37, are 100 provided with rollers 39 which engage a roller path or groove cut into the inside members 3. On the first movement of the ram the rollers 39 attached to levers 36 and 37 are forced up an inclined portion 45 of said groove thus causing 105 the clamping portion of the levers 36 and 37 to compress and hold the back end of the tin plates during substantially full traverse of the ram 5, whilst the said ram is pushing the loaded inner container into its tubular metal case. When 110 the ram has completed its stroke and the inner container is home in the tubular case the rollers 39 of levers 36 and 37 engage another inclined portion of the groove cut into the side members 3, the levers thus releasing their grip on the tin 115 plates, ready for the return of the ram to its normal position, which is brought about by the further rotation of cam 13, which also operates the tilting table 8, by means of the lever 11 and link 10, allowing the table to come into a vertical 120 position to discharge the full tubular container with its contents down the gravity rollers provided. Further rotation of shaft 27, together with cams 30 and 13 causes the ram 5, the back-stop 4 and the tilting table 8 to resume their 125 normal positions, whereupon clutch automatically disengages the shaft 27 from the cams 30 and 13.

It should be noted that the compression of the plates into the inner container is effected as follows. Firstly the back ends of the plates are compressed and clamped by means of the levers 36 and 37 as described above. Then as the ram moves forward the front portion of the papier 130 mâché container passes under the weighted roller 19, which partially compresses the plates. Further compression is obtained by virtue of the ram 5 forcing the container, together with the tin plates, between the fixed gap of the rotatable rollers 6 and 7.

An alternative method by which tight packing of tin plates may be accomplished, although not preferred, is one in which a metal outer container of the shape shown in schematic section in the accompanying Figure 7 is employed in place of 145 a tubular outer container, the papier mâché container being first placed in the open metal container and the tin plates afterwards loaded into the inner container, the lid *L* of the metal outer case being then closed by means of a suitable 150

press which compresses the plates down within the papier mâché container. Before the press is released the lid is sealed for example by means of seaming tools as described in United States

5 Patent No. 1,730,070.

What we claim is:—

1. A method of packing tin plates wherein a stack of tin plates is first placed in an inner container whose internal dimensions are substantially equal to the overall dimensions of the stack of plates when flattened, the lid of the container being closed as far as the buckle or set of the plates will permit, the stack then being flattened and the lid closed by compression, and the inner 10 container forced into a tubular outer container.

15 2. A method of packing tin plates which consists in stacking the plates in a shallow box-like inner container located within a metal outer container and the depth of said inner container being substantially equal to the thickness of a stack 20 of plates when flattened, partially closing the lid of said inner container, placing in position the lid of the outer container and applying pressure to the latter to flatten the stack and sealing down 25 the lid of the outer container.

3. A machine for packing tin plates comprising a frame, a pair of rollers mounted in said frame, said rollers being substantially parallel one to the other and spaced apart a predetermined amount, means for locating the open end 30 of a tubular outer container opposite the gap between said rollers and means for propelling an inner container filled with tin plates through said gap into said outer container.

35 4. A machine as claimed in claim 3 in which the gap between the rollers is adjustable.

5. A machine for packing tin plates comprising a frame, a pair of rollers mounted in said frame, said rollers being substantially parallel 40 one to the other and spaced apart a predetermined amount, means for locating the open end of a tubular outer container opposite the gap between said rollers, means for propelling an inner container filled with tin plates through said gap into said outer container and means for applying an initial pressure to the inner container and plates thereon before said container is propelled through the gap between the rollers.

6. A machine for packing tin plates comprising a frame, a pair of rollers mounted in said frame, said rollers being substantially parallel one to the other and spaced apart a predetermined amount, means for locating the open end 50 of a tubular outer container opposite the gap between said rollers and a ram, which engages the front edge of an inner container, filled with tin plates, for propelling said container through said gap into said outer container.

60 7. A machine for packing tin plates comprising a frame, a pair of rollers mounted in said frame, said rollers being substantially parallel one to the other and spaced apart a predetermined amount, means for locating the open end of a tubular outer container opposite the gap between said rollers, means for propelling an inner container filled with tin plates through said gap into said outer container and means for clamping the front edge of the container during the movement thereof.

70 8. A machine for packing tin plates comprising a frame, a pair of rollers mounted in said frame, said rollers being substantially parallel one to the other and spaced apart a predeter-

mined amount, means for locating the open end of a tubular outer container opposite the gap between said rollers, a ram, which engages the front edge of an inner container filled with tin plates, for propelling said container through said gap into said outer container, a clamping lever or levers pivoted to the ram and fixed cam means adapted to engage said lever or levers to cause the latter to clamp the inner container at or near the commencement of stroke of the ram and to release said inner container at or near the end of the stroke of the ram.

80 9. A machine for packing tin plates comprising a frame, a pair of rollers mounted in said frame, said rollers being substantially parallel one to the other and spaced apart a predetermined amount, means for locating the open end of a tubular outer container opposite the gap between said rollers, a ram for propelling an inner container filled with tin plates through said gap into said outer container, stop means adapted to locate the inner container on the bed of the machine while being filled with tin plates and means for automatically removing said stop means from the path of the container at or before 100 the commencement of the stroke of the ram.

90 10. A machine for packing tin plates comprising a frame, a pair of rollers mounted in said frame, said rollers being substantially parallel one to the other and spaced apart a predetermined amount, means for locating the open end of a tubular outer container opposite the gap between said rollers, a ram for propelling an inner container filled with tin plates into said outer container and means for automatically 105 discharging a filled outer container from the machine.

105 11. A machine as claimed in claim 10 in which the means for automatically discharging a filled outer container comprise a tiltable platform normally lying substantially in the plane of the bed of the machine and adapted to carry a tubular outer container while the latter is being filled and means actuated upon the completion of the stroke of the ram for tilting said platform into 120 a substantially vertical position.

115 12. A machine for packing tin plates comprising a pair of substantially parallel rollers spaced apart by a predetermined amount, means for locating the open end of a tubular outer container opposite the gap between said rollers, a ram for propelling an inner container filled with tin plates through said gap into said outer container, stop means adapted to locate the inner container on the bed of the machine and being automatically 125 removed from the path of the container at or before the commencement of the stroke of the ram, and a tiltable platform carrying a tubular outer container while the latter is being filled and being tilted into a substantially vertical 130 position upon the completion of the stroke of the ram, the ram, stop means and tilting platform being actuated in sequence from a common cam-shaft.

135 13. A machine as claimed in claim 12 and comprising a control lever, a clutch adapted to engage the cam shaft with a continuously rotating driving shaft upon actuation of said control lever, said clutch being adapted to be automatically disengaged upon completion of a cycle of 140 operations.

NORMAN BISHOP.
ERNEST R. GARRON.
